(57) **CLAIM**

The ornamental design for an display screen portion with animated graphical user interface, as shown and described.

DESCRIPTION

FIG. 1 is a front view of a first image of a first embodiment of an display screen portion with animated graphical user interface showing my new design;

FIG. 2 is a front view of a second image thereof;

FIG. 3 is a front view of a third image thereof;

FIG. 4 is a front view of a first image of a second embodiment of an display screen portion with animated graphical user interface showing my new design;

FIG. 5 is a front view of a second image thereof;

FIG. 6 is a front view of a third image thereof;

FIG. 7 is a front view of a first image of a third embodiment of an display screen portion with animated graphical user interface showing my new design;

FIG. 8 is a front view of a second image thereof;

FIG. 9 is a front view of a third image thereof;

FIG. 10 is a front view of a first image of a fourth embodiment of an display screen portion with animated graphical user interface showing my new design;

FIG. 11 is a front view of a second image thereof; and,

FIG. 12 is a front view of a third image thereof.

In the first embodiment, the appearance of the transitional image sequentially transitions between the images shown in FIGS. 1 through 3. In the second embodiment, the appearance of the transitional image sequentially transitions between the images shown in FIGS. 4 through 6. In the third embodiment, the appearance of the transitional image sequentially transitions between the images shown in FIGS. 7 through 9. In the fourth embodiment, the appearance of the transitional image sequentially transitions between the images shown in FIGS. 10 through 12. The process or period in which one image transitions to another image forms no part of the claimed design. In FIGS. 1 through 8 and 10 through 12, the greyscale fill located within the claimed rectangular area represents a contrasting appearance to regions within the claimed rectangular area in which no greyscale fill is shown.

The broken line showing including the text and portions of the graphical user interface, as well as portions of the display screen are for the purpose of illustrating portions of the article, and form no part of the claimed design.

1 Claim, 12 Drawing Sheets
